UNITED STATES PATENT OFFICE.

FERDINAND PHILIPS, OF PHILADELPHIA, ASSIGNOR OF ONE-HALF TO J. B. FORD, OF HITES, PENNSYLVANIA.

GAS-GENERATOR.

SPECIFICATION forming part of Letters Patent No. 277,926, dated May 22, 1883.

Application filed February 16, 1882. (No model.)

To all whom it may concern:

Be it known that I, FERDINAND PHILIPS, a citizen of the Empire of Germany, but domiciled at Philadelphia, in the county of Philadelphia and State of Pennsylvania, have invented certain new and useful Improvements in Gas-Generators, of which improvements the following is a specification, reference being had to the accompanying drawings, which form part hereof.

My improvements pertain to that class of gas-generators which are called more commonly "producers," because they are employed to generate or produce from the imperfect combustion of solid fuel carbonic oxide or gaseous fuel for application in separate apparatus, to which this gaseous fuel is conducted from the generator or producer without being ignited until it reaches the place where it is to be consumed; and it is the object of my invention to perfect the construction of such producers in several respects, so as to improve their operation, to prevent their rapid destruction, and to facilitate access to the interior for the purpose of removing ashes, clinkers, &c.

As a good exemplification of perhaps the best known recent improvements in gas-generating furnaces, and at the same time of the serious difficulties or defects which still characterize them, I refer to Letters Patent No. 213,318, dated March 18, 1879, to Brook and Wilson. This furnace has been introduced in this country, and may be regarded as the most advanced heretofore in use. Without advertising to minor defects in it, the Brook and Wilson furnace wears away rapidly, because its numerous fittings cannot be kept tight enough to prevent the escape of the subtle gases generated within it, and it cannot be cleaned out except with great difficulty, and not only with a waste of fuel, but by exposing the workmen to an almost intolerable heat and to serious personal risk. While unnecessarily complicated in its interior arrangement, it is imperfect also in its provisions for being opened, cleaned, and closed again, requiring, when it is to be cleaned, the insertion of crupper-bars, which must be driven across the furnace through the fuel at a point as near as may be between the unconsumed

fuel and the ashes and clinkers, these bars forming, in fact, a temporary grate to support the unconsumed fuel while the single ash-port below is open for the removal of the accumulated ashes and clinkers. Upon the opening of this door the ashes and a considerable portion of fuel shaken down by the insertion of the crupper-bars rushes out at the open port, occasioning difficulties that will readily be appreciated, these difficulties being even greater when an attempt is made to clean this furnace without first inserting the crupper-bars. The workman has now not only to contend with this avalanche of ashes and incandescent fuel, but also to break up and rake out as well as he can the masses of clinker which are always found at such times to have accumulated all around the lower part of the furnace, and in breaking up and dislodging which he is constantly bringing down first incandescent fuel, and ultimately the fresher parts of the charge. Working only from one side and through a comparatively narrow opening, it is of course impossible to remove the clinker thoroughly. Under such conditions the cleaning of such a furnace is not only a laborious and trying task, but it involves a very serious loss of time not only while the operation of the furnace is suspended, but in restoring it again to active operation. Again, when in operation this furnace is found to leak so much as to burn away the walls and the iron fittings—such as the door, its frame, and the crupper-bar channels—and its wear is actually rapid, aside from the escape and waste of gas. But in my improved gas-generator I have cured all of these difficulties—that is to say, I prevent leakage or waste of gas and the above-mentioned attendant destruction of the furnace and its fittings, I obviate the necessity of providing for the use of crupper-bars and the disturbance of the charge attendant upon their introduction, I prevent the tumbling down and out of the ashes and incandescent fuel when the port is opened and the attendant hardships upon the workmen above mentioned, and I afford ready access to every point in the lower part of the furnace, rendering it easy to remove all the clinkers therefrom very quickly, as well as with facility,

and I simplify the construction of the furnace itself very greatly.

In the drawings annexed hereto and forming part hereof I have shown, in the best form known to me, my improved gas-generator, Figure 1 being a vertical section through the apparatus on the line *xx* of Fig. 3, Fig. 2 being an elevation with the shell partially broken away to show a section on the line *yy*, Fig. 3, Fig. 3 being a cross-section through the apparatus, giving a top view of the tuyeres in position; and Fig. 4 is a plan of the discharge-pipe or downtake.

I construct the producer proper in the form shown in the drawings, and in general more or less familiarly known in blast-furnaces—namely, with a cylindrical central section, a coned top section, and an inverted cone lower section, but the depth and convergence of this cone being such as to embody one of the fundamental principles of my invention, as herein-after described. This producer is built up of fire-brick, *f*, upon a suitable foundation, as is well understood, and inclosed with a shell, *m*, of boiler-iron. The producer is fitted at the top with a charging-hopper, *H*, and a bell, *b*, such as are used in blast-furnaces, and at the bottom is provided with a grate, *g*, so proportioned and located as to leave a solid hearth around the base, as seen especially in Fig. 3. Beneath the grate *g*, I provide an ash-pit, *a*, having a suitable door, *d*. A channel, *c*, is formed in and extends across the foundation, communicating at its outer end with a blower, *B*, and from this blower *B* a jet of air, or air and steam, is forced into the channel *c*, and by means of a pipe, *P'*, is led into the ash-pit and underneath the grate, through which it passes up into the fuel. I also connect with the channel *c* the tuyeres *P P P P*, through which are introduced above the grate lateral jets of air, or preferably air and steam, from the blower *B*. Two openings, *o o*, one opposite the other, are cut through the shell *m* and brick-work *f* into the interior of the furnace above the grate *g*. Each of these openings is fitted externally with a strong cast-iron door, *d*, which can by proper fittings be secured in place or removed, as desired, and between each door and the adjacent opening into the furnace I interpose a heavy block, *t*, of refractory material, fitting the opening and protecting the door, as well as confining the fuel or the ashes within or nearly within the lines of the bottom of the furnace. At the top of the furnace I lead off the gaseous fuel through a pipe, *n*, into the downtake *D*, from which it passes through a tunnel, *C*, to the point at which it is to be ignited and consumed. The valve *v* in the downtake is operated, as required, to open or shut off the communication between the tunnel *C* and the interior of the producer. The stem *s* of the valve *v* passes through the cover of the downtake, and in this cover I provide a series of holes, as shown in Figs. 1 and 4, which holes I cover respectively

with loose lids, sealing them with sand, so that while serving to prevent the escape of gas in the normal operation of the producer, they will act as safety-valves in case of a back-flow of pressure caused by any disturbance of the operation. To admit of the inspection of the interior of the producer, and also to permit of the introduction of stoking-irons, when required, I provide openings in the top of the producer and cover them with movable lids *i i*. I also provide a spy-hole on the outer end of each of the blast-pipes *P P*, closing them with mica windows, so connected that they can be swung aside and a stoking-iron passed through the tuyere into the producer, thus enabling me not only to inspect all parts of the producer during the operation, but to reach parts of it, as may be required, for the dislodgment of clinker or other obstruction.

While I do not limit myself to a particular depth or angle of inclination toward the hearth in what I may call the "bosches" of my producer, (the lower section,) as these might vary slightly with the use of different fuels, yet I do prescribe the rule derived by me from actual practice with anthracite and bituminous coal, and forming the basis of this feature of my invention—that is to say, the angle of inclination will of course determine the depth, and this inclination must always be such that the sides will sustain the fuel on the principle of the skewback of an arch, the arch being represented by the bottom of the incandescent fuel. In the drawings this depth and inclination of the bosches are exemplified by an angle of fifteen degrees with the central axis, or one hundred and five degrees with the plane of the hearth. This rule being observed, it will be found in the operation of the producer that the line of support will rise with the consumption of the fuel and virtually form an ash-pit below this line, the effect of this support of the charge being not only to cause or permit the ashes and scoriae to settle down toward the bottom of the producer without being tightly compacted by the superincumbent weight of the charge, but also, as I have found by actual practice, to cause the fuel to settle down so gradually that the arch is maintained; and even when the doors are opened to clean the producer the ashes and scoriae are removed without necessarily disturbing or breaking down this arch, and consequently without the loss of unconsumed fuel, and, in case the fuel should fall down upon the hearth, yet it will be found that by reason of the given inclination of the bosches it will not rush out through the openings, but will simply bank up across the reduced area of the bottom of the producer, and even across the openings themselves without coming out even so far as to in any way prevent the proper replacement of the tiles and the closing of the doors. In cases where the arch of fuel does not break down, the producer is simply closed after being cleaned, and a stoking-iron introduced at such point through

the tuyeres or through the top of the producer, as may best serve to loosen the fuel and let it down upon the hearth.

The support afforded by the boshes, as just described, is so positive and absolute that I have no occasion to use crupper-bars, and as I make no provision for their use I am enabled to simplify the construction of the producer very materially by the omission of fittings that would otherwise be necessary, and I avoid the difficulties from such fittings, which I have already indicated in the operation of the producer.

The operation of my improved gas-producer is as follows: A fire is built on the grate *g*, and the fuel gradually fed in upon this fire through the charging-hopper *H* and bell *b*, operated in the well-known manner indicated in Fig. 2. The valve *v* in the downtake *D* is opened, so as to give an outlet through the tunnel *C* to the chimney leading from the combustion-chamber into the atmosphere. The blast or jet, being turned on through the blower *B*, gradually passes from the channel *c*, through the pipe *P'*, beneath the grate up into the fuel, and through the tuyeres *P P P P* above the grate into the fuel from different points, the several jets being thoroughly diffused through the fuel and promoting the conversion of the carbonic acid, forming more actively at the lower part of the producer into carbonic oxide, and forcing it upward until it passes off through the pipe *n* into the downtake *D*, its exit being regulated by the valve *v*, as the quantity produced increases with the increasing incandescence and roasting of the solid fuel with a rapidity greater or less, according to the regulation of the blast from the blower *B*. The best practice will be observed by limiting the depth of the charge in the producer to about the middle of the central section until the accumulation of ashes in the lower section has attained some depth, when they will begin to settle down and additional fuel may be charged in, and as the ashes below continue to accumulate the fresh fuel above may be added until it is as high as the lower line of the top section of the producer. When the accumulation of ashes has increased so much as to appreciably reduce the active generation of the gaseous fuel it is proper to clean the producer, and for this purpose I shut off the blast, and after a short interval, allowing for the passing off of the gas in the upper part of the producer, I close the valve *v* in the downtake to shut off the communication with the tunnel *C*. I then remove the doors *d d* and the tiles *t t*, when the ashes

will be found banked across the openings through the producer, and not only can the ashes be readily removed through these openings, but any scoriae or clinkers that have accumulated can be readily broken up at whatever part of the producer they may be lodged, and with great facility pushed out by the workman through the side opposite to him, or drawn out through the side next to him, until the hearth and grate are thoroughly cleaned. It is here that the advantages of my improvements are most conspicuously exhibited, as I find that the fuel has been much more deliberately and thoroughly reduced to ashes than heretofore, while the scoriae have not the properties and do not present the difficulties of removal usually found in gas-producers heretofore. This is due in my system very largely to the automatic gradual and uniform feeding down of the ashes and scoriae, followed gradually by the fuel during the operation, and this feeding down of the fuel demands a cylindrical body and a lower section, such as already described. The shape of the upper section may be varied as convenience or other circumstances may dictate, so far as is consistent with the above-described form of the other parts of the producer.

Having thus described the nature and object of my invention, what I claim as new, and desire to secure by Letters Patent, is, as improvements in the construction and operation of gas-producers—

1. The improved gas-generator, constructed substantially as described, with two openings on opposite sides thereof, the doors, and the removable tiles interposed between the doors and the interior of the furnace, substantially as and for purposes set forth.

2. The improved gas-generator, constructed substantially as described, with a cylindrical body, a lower section or boshes in the form of an inverted cone converging toward the hearth on the principle of the skewback of an arch, and at an angle substantially such as prescribed, and having openings in opposite ends of the lower section, with doors, and removable tiles interposed between the doors and the interior of the furnace, substantially as and for the purposes set forth.

In testimony whereof I affix my signature in the presence of two witnesses.

FERDINAND PHILIPS.
